US0D1041946S

(12) **United States Design Patent** (10) Patent No.: **US D1,041,946 S**
(45) Date of Patent: ** Sep. 17, 2024

(54) **SHAVING RAZOR CARTRIDGE DISPENSER**

(71) Applicant: **The Gillette Company LLC**, Boston, MA (US)

(72) Inventors: **Sharika D. Anderson**, Boston, MA (US); **Daniel De Marchi Martins Goncalez**, Sao Paulo (BR); **Richard Kevin Sennett**, Abington, MA (US)

(73) Assignee: **The Gillette Company LLC**, Boston, MA (US)

(**) Term: **15 Years**

(21) Appl. No.: **29/829,853**

(22) Filed: **Mar. 8, 2022**

(51) LOC (14) Cl. **06-04**

(52) U.S. Cl.

USPC **D6/526**

(58) **Field of Classification Search**

CLAIM

The ornamental design for a shaving razor cartridge dispenser, as shown and described.

DESCRIPTION

FIG. 1 is a first perspective view of a design of a shaving razor cartridge dispenser of the present invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is second perspective view thereof; and,

FIG. 9 is an environmental view thereof.

The broken lines shown illustrate shaving razor cartridges positioned with the dispenser and form no part of the claimed design.

1 Claim, 7 Drawing Sheets
